CLAIM

The ornamental design for a telephone, as shown and described.

DESCRIPTION

FIG. 1 is a top, front and side perspective view of a telephone showing our new design in an "at-rest" or "off" position;

FIG. 2 is a front perspective view thereof in "on" position;

FIG. 3 is a similar perspective view thereof in a second "on" position;

FIG. 4 is a front elevational view thereof on an enlarged scale in the "off" position;

FIG. 5 is a side elevational view thereof from the left side of FIGS. 1 and 4;

FIG. 6 is a right side elevational view thereof;

FIG. 7 is a rear elevational view thereof;

FIG. 8 is a bottom plan view thereof; and

FIG. 9 is a top plan view thereof.
